UNITED STATES PATENT OFFICE.

BENJAMIN W. TUCKER, OF SOUTH ORANGE, NEW JERSEY, ASSIGNOR TO CORONA TYPE-WRITER COMPANY, INC., A CORPORATION OF NEW YORK.

TYPE-WRITING MACHINE.

1,283,367.

Specification of Letters Patent. Patented Oct. 29, 1918.

Application filed April 22, 1916. Serial No. 92,894.

To all whom it may concern:

Be it known that I, BENJAMIN W. TUCKER, a citizen of the United States, and a resident of South Orange, county of Essex, and State 5 of New Jersey, have invented certain new and useful Improvements in Type-Writing Machines, of which the following is a full, clear, and exact description.

This invention relates more particularly 10 to the carriages of typewriting machines.

One of the main features of the invention is to provide a carriage which is extensible to adapt platens either extensible or of relatively different lengths to be supported by 15 said carriage in order that work sheets of various lengths may be written upon and which carriage is adapted to travel various normal or abnormal distances corresponding to the degree of extension thereof, thereby 20 permitting the writing to take place throughout substantially the length of the platen without requiring the paper to be shifted from one part of the platen to another part.

Another object of the invention is to provide simple and efficient means whereby the platen may be made in sections and properly held relatively to each other to increase or decrease the length thereof and which platen 25 is supported at its ends by extensible portions of the platen carriage.

Other objects of the invention are to provide simple and efficient means whereby the carriage may be extended and held in such 30 extended positions; to provide a shiftable paper apron; to provide an extensible scale adapted to travel with the carriage; and to provide simple means for supporting paper fingers to coöperate with the platen and carriage.

A further object of the invention is to provide a simple and efficient escapement mechanism which is so constructed that the carriage may be extended or collapsed and said 35 escapement mechanism operated to permit letter space movement of the carriage in either its collapsed or extended condition.

A still further object of the invention is to provide a carriage which is particularly 40 adapted for small portable typewriting machines, wherein certain parts of the carriage are adapted to be moved from a normal operative position to a more compact one, and wherein a long carriage would naturally de-

stroy the compact portability of such a machine.

A still further object of the invention is to provide a carriage which is simple in construction and which may be readily made and assembled.

In the drawings, Figure 1 is a plan view of one form of carriage embodying the invention showing the parts in a collapsed condition.

Fig. 2 is a front elevation.

Fig. 3 is an end view.

Fig. 4 is an end view of the side of the carriage opposite to that shown in Fig. 3.

Fig. 5 is a vertical section showing the carriage and the platen in a collapsed condition.

Fig. 6 is a vertical section similar to Fig. 5, except that the carriage is shown in an extended position and the platen lengthened to correspond with the extension of the carriage.

Fig. 7 is a detail side elevation of the part of the operating means for the escapement dogs and the means whereby the dogs may be released from the escapement rack.

Fig. 8 is a fragmentary end view of the parts shown in Fig. 7.

Fig. 9 is a vertical transverse section through the carriage.

Fig. 10 is a fragmentary plan showing the extensible bar for operating the escapement dogs.

Fig. 11 is a fragmentary front elevation of the bar shown in Fig. 10.

Fig. 12 is a fragmentary elevation of an extensible scale adapted for use with the extensible carriage.

Fig. 12^a is a transverse section through the scale.

Fig. 13 is a detail elevation of a socket piece for one end of the platen.

Fig. 14 is an end view of the platen part or socket piece shown in Fig. 13.

Fig. 15 is an end view of the platen end or socket piece for the end of the platen opposite to that shown in Fig. 13.

Fig. 16 is a detail section of a part of the mounting for one end of the platen.

Fig. 17 is a sectional plan of the escapement dogs and carriers therefor showing how two sets of dogs may be mounted to move in unison.

Fig. 18 is a fragmentary elevation, partly

in section, of one part of the escapement mechanism.

Fig. 19 is a vertical section through the dog carrier shown in Fig. 18.

Fig. 20 is a fragmentary rear elevation of the carriage; and

Fig. 21 is a fragmentary transverse section of Fig. 20 showing the means whereby the paper apron may be adjusted lengthwise of the carriage.

While the invention is intended more particularly for a writing machine which is compact and portable in order that the carriage when in a collapsed condition will not be of greater length than the ordinary carriage and thereby interfere with the compact and portable features of such machines, it will be understood that the invention is adapted for use in connection with writing machines of various kinds and constructions.

The bed 10 may be supported in any desired way to adapt the same for a platen or other case shift, or to be movable from a normal operative position to a more compact one, or otherwise, as preferred. On the bed 10 are two track members 11 and 12, one located at the front part of the bed 10 and the other at the rear thereof. A carriage 13 is adapted to travel along the track members 11 and 12 under the tension of a suitable motor, as the usual spring drum, which is not shown, as it forms no part of the present invention. The carriage has two relatively movable base members 14 and 15. These members are substantially U-shaped in cross section, and one member, as the member 15, is adapted to fit within the other member 14. The member 14 is offset for the greater part of its horizontally arranged portion 16, so that said member 14 bears on the outer surface of the member 15 at the corners of said member 15. The vertical walls 17 of the member 14 are also offset from the vertical walls 18 of the member 15 for a part of their height and at their lower edge bear against outwardly extending flanges 19 of said member 15. An angular substantially L-shaped plate 20 is secured to each vertical wall 17 and has one portion thereof of each plate fitting under the flange 19, serving to provide a guiding surface for the member 15 when the latter is moved relatively to the member 14 for the purpose of extending or lengthening the carriage. Each L-shaped member 20 may have substantially L-shaped brackets 21 secured thereto, the lower ends of said brackets being adapted to fit under the horizontally extending portion of the track members 11 and 12, serving to hold the carriage properly to said track members during the travel thereof. A plurality of shafts 22 are journaled in the vertical walls 18 of the carriage base member 15, and held to each of said rods are rolls 23 which are adapted to ride

in grooved parts 24 of the track members 11 and 12, in order to assist in permitting the carriage to travel easily and properly along said track.

On the carriage base member 14 at one end thereof is secured an upright or end bracket 25, and on the inner base member 15 at one end thereof is a similar end piece or bracket 26. These brackets are adapted to form the ends for the carriage and are movable toward and from each other, according to whether the carriage is extended or shortened. A platen 27 is adapted to be rotatably supported in the end brackets 25 and 26. This platen may be made of a plurality of sections arranged end to end so as to be extended the length desired. One or more of the platen sections may be provided of relatively different lengths, adapted to be held in the carriage end brackets 25 and 26 when the carriage is in its extended or shortened condition as preferred. As shown, the platen 27 comprises a plurality of sections or parts 28, 29 and 30, when in an extended condition, or of only two sections when shortened and of a normal size, but it will be understood that the number of these sections may vary. Each section of the platen may be of the usual construction, having an impact rubber or other member 31, supported by a tubular or other form member 32. A cylindrical hub member or socket piece 33 is secured to one end of the section 28, and said piece 33 is provided with a central tapered opening into which is adapted to fit the tapered end 34 of an adjustable screw or element 35. On the outer end of the screw 35 is a knurled head 36, by which the screw may be adjusted for engagement or disengagement with the hub member 33, and said screw 35 may engage a threaded opening 37 in the plate or bracket 25 of the carriage. The opposite end of the section or platen member 28 is provided with a female socket piece 38. The socket pieces 33 and 38 form supports for the platen form 32, which is held thereto, and the socket piece 38 has a central opening of a more or less extended character which is adapted to receive the stem or shank 39 of a male socket piece 40, forming an end support for the second platen section. This socket piece 40 may have a pin or dowel 41, which is adapted to enter an aperture in the socket piece 38, so that the two socket pieces 38 and 40 will not only have a substantial interlocking connection of such a nature as will hold the two sections in proper alignment, but also through one or more of the dowel pins 41, will cause both members to rotate in unison. At the opposite end of the section 29 is a socket piece 42 similar in construction to the socket piece 38 and adapted to engage said socket piece 42 is a socket piece or member 43 similar to the socket piece 40, said socket piece 43

43 being securely held so as to form a part of the platen section or member 30. If the platen comprises more than three sections an additional section may be provided, either of 5 the same or of a different length from the section 29, having similarly arranged end pieces, one serving as a male member and the other as a female member, and which may be connected together or disconnected as 10 may be required.

In Fig. 6 the platen comprises three parts or sections, while in Fig. 5 the middle section is removed and the two outer sections, that is sections 28 and 30, are brought together when it is desired to make the carriage and platen of the usual length. At the outer end of the section 30 is a socket piece or member 44 corresponding somewhat to the end socket piece 33 of the section 28, except that instead of annular boss being arranged on the outer surface of the flange, an elongated portion or boss 45, is provided, Figs. 13 and 14, which is adapted to enter a slot or groove 46 in the boss 47 of a sleeve 25 48. The purpose of the elongated portion or boss 45 is to adapt the platen as a whole to be readily inserted in the sleeve or removed therefrom, and by reason of said boss being elongated the sleeve and platen 30 may be made to rotate together.

The sleeve 48 is held in an opening in the carriage end 26 and said sleeve is threaded at 49 at one end thereof, and said threaded opening is engaged by the threaded portion 50 of a screw 51. The screw 51 has a tapered portion 52 at one end adapted to engage a tapered opening in the socket piece 44, and at the opposite end of said screw is a knurled head 53. A knob 54 is held by a screw 55 40 or otherwise to the sleeve 48 and screw 51 to adapt the knob and sleeve as well as the screw 51 and the platen as a whole to be rotated manually by hand and to move the work sheet about the platen in the usual way. By 45 releasing the screws 35 and 51 from engagement with the end socket pieces the platen may be removed by sliding the boss 45 to one side out of the groove 46, which will permit the section 29 to be removed or inserted 50 in place, and if removed will permit the section 30 of the platen to be connected with the section 28 to shorten the platen, as shown in Fig. 5. In this figure the carriage members 14 and 15 have been moved relatively to each 55 other to collapse the carriage, and by tightening the screw 51 the platen as thus shortened may be properly supported in the carriage between the screws 51 and 35.

The carriage may be held in its lengthened 60 or shortened position in any desired way. As one means, a rod 56 is rotatably held in a lug 56^a extending downwardly from the horizontal plate portion of the carriage member 15 and the carriage end bracket 26. On the 35 rod 56 is a dog 57, Figs. 6 and 9, which is

adapted to be moved into engagement with one or more openings, as 58, in the member 14, according to the different extensions of the carriage to adapt the carriage for the different lengths of platens, whether the 70 platen is made up of a plurality of sections, or a series of platens are employed of relatively different lengths to adapt one platen to be substituted for another. At the other end of the rod 56 is a lever 59, the upper end 75 of which is provided with a finger portion 60 to adapt the dog to be released from engagement with the openings, there being a spring if desired, tending normally to keep the dog in engagement to lock the two carriage members 14 and 15 against relative movement.

One of the important features of the present invention is the provision of means whereby the carriage may have relatively 85 different lengths of feed, according to the length of the carriage and platen. That is, the letter feeding mechanism is so constructed that the carriage may travel normal and abnormal distances corresponding 90 exactly to its length. If the carriage is short or of normal length, as shown in Fig. 5, the letter feed mechanism is so constructed that the carriage may be fed with a letter space movement along the carriage bed to the usual 95 extent for ordinary writing; but if the carriage is extended as shown in Fig. 6, the same letter feed mechanism without special adjustment is adapted to cause the carriage to feed a greater extent, according to the extent to which the carriage and platen have 100 been lengthened.

As one means for accomplishing normal and abnormal travel for the carriage I provide a rack 61 on the carriage bed 10, the teeth of which are adapted to be engaged by the two sets of dogs 62 and 63, the sets of dogs 62 being mounted upon a dog carrier 64, and the set of dogs 63 being mounted upon a dog carrier 65. The sets of dogs 62 110 and 63 and the carriers 64 and 65 for said dogs are similarly constructed. Each carrier is in the form of an arm, which is pivoted at 66 at one end, and is guided in a bracket 67 at the other end and both are 115 mounted on the inner carriage base member 15 to partake of its collapsed or extended movement. A fixed dog 68 is held to each carrier and a loose or limber dog 69 is pivotally held to each carrier, the limber dog 120 being forced in one direction by means of a spring 70, while the carrier itself is forced in one direction by a spring 71. The fixed and limber dogs and the carrier 64 operate in the usual way, and taken as a single element the dogs and either of the carriers 64 and 65 are substantially the same as embodied in the Corona typewriter, differing, however, from the said Corona typewriter in that there are two dog carriers instead of 125 130

one which permit of an abnormal travel of the carriage, and the present construction differs further in that the rack is mounted upon the carriage bed, and the dogs and carrier mounted upon the carriage bed to travel therewith, though the reverse of this construction may be employed if desired. The dog carriers are each provided with a lug or arm 72, and these arms are connected by a rod 73 whereby the two dog carriers move in unison, and the dogs of said carriers are so positioned that they may both engage the teeth of the rack at the same time, or one only, according to the position of the carriage relatively to the rack. In this way the carriage may be made to travel along the bed through the action of one set of dogs and the usual tension mechanism, and for a part of its travel both sets of dogs may engage the teeth of the rack and the carriage may still travel until the first set of dogs has left the rack, while the letter spacing movement may be controlled by the second set of dogs. Thus the two sets of dogs may operate in unison and at the same time on the rack or either set of dogs operate to control the letter space movement of the carriage. By this means long sheets of paper or large envelops may be written upon substantially throughout their entire width or length without increasing the length of the rack, and said means adapts the carriage to be lengthened or shortened without interfering in any way with the letter feed movement thereof.

The escapement dogs may be operated in any desired way. The carriage bed 10 may be provided with a slot 74, in which is adapted to reciprocate an element 75. This element 75 is operatively connected to the universal bar, not shown, and is adapted to be moved at each depression of the key-operated levers or the space bar, in the usual way. The element 75 is adapted to engage a transversely extending bar 76. This bar 76 is made in two parts so as to be extensible, as best shown in Fig. 6, and Figs. 9 to 11. The bar 76 has two members 77 and 78. The member 78 is provided with an enlarged end 79 having bent lips or portions to fit over the body of the member 77, and the member 77 has an enlarged end 80 provided with overlapping engaging portions adapted to span and slide upon the body of the bar member 78. An arm extends upwardly from the member 77 and is pivotally held at 81 to the carriage end or bracket 25, and the member 78 has its outer end extending upward and is pivotally held at 82 to the carriage end bracket 26. A lever 83 is pivotally held on the screw or pin 82, and has a substantially U-shaped portion 84, which is adapted to engage one edge of the upwardly extending portion of the carriage release bar 76 and in such a way that said

bar may be moved inwardly independent of the movement of said lever 83. The transversely extending bar 76 is normally forced in one direction by a spring 85, while the lever 83 is normally forced in one direction 70 by an independent spring 86, there being a stop 87 adapted to limit the movement of the lever 83 and the carriage release bar in one direction. As the element 75 is operated by the universal bar, it will rock the 75 extensible bar 76 on its pivot screws, independent of any movement of the lever 83, and such movement of said bar will engage the fixed dog 68 of either one or both sets, so as to permit the carriage to be letter 80 spaced in the usual way. The release of the escapement independent of letter space movement may be readily accomplished by means of the lever 83, which will move the release and operating bar 76 in a manner 85 similar to its movement by the element 75.

The carriage may be provided with the parts usually coöperating therewith to adapt the work sheet to be properly held about the platen. Where the platen is extensible, as in the present construction, it is desirable that the paper apron be also either extensible or that it be adjustable to permit it to be substantially centrally located with respect to the position of the 95 carriage ends. As shown, the paper apron 89 is adjustable lengthwise of the platen. The paper apron is in the form of the usual plate, adapted to direct the paper properly about the platen, and at the forward end 100 thereof may have detachable or otherwise mounted thereon a feed or pressure roll 90, adapted normally to hold the work sheet so as to move with the platen for line spacing or otherwise. The paper apron 89 curves upwardly and rearwardly in substantially the form of an ogee curve, and is held to brackets 91. The brackets 91 extend upwardly from a slide 92. This slide 92 has ends turned inwardly and adapted to engage a substantially T-shaped guide 93 mounted upon the member 14 of the carriage. A dog 94 is held to a rod 95, and said dog has its lower end adapted to engage an aperture or opening in the guide 93 whereby the paper apron 110 89 and the slide 92 may be adjusted relatively to the platen and by means of the dog 94 positively held in such adjusted position. The dog is adapted to be released for adjustment by means of a finger lever 96, 115 and said dog is normally forced to an engaging position by means of a spring 97 arranged around the rod 95 or in any other desired way.

The paper apron 89 may be moved on its 125 pivot rod 95 by means of a cam device 98, said device being held to the upper end of a guide bracket 99 or otherwise supported, and said device 98 may be normally forced in one direction by means of a spring 100, 130

there being a spring or other means provided whereby the pressure roll may be normally forced against the platen.

An extensible scale may be mounted upon the forward end of the carriage brackets 25 and 26. This scale may consist of two members 101 and 102. These members slide one upon the other, and one of said members, as member 102, may have its upper and lower edges at one end bent over to form overlapping lips 103, and the member 101 may have overlapping lips 103^a by which the two members are slidingly held together. One member of the scale may be held to one of the end pieces, as the member 102 to the end piece of the carriage 26, and the other member 101 of the scale may be held to the carriage end piece or bracket 25. Thus, as the carriage is extended, the end pieces will carry the respective members of the scale therewith.

The carriage may be also provided with paper fingers 104. These paper fingers at their upper ends may have rollers 105 to engage the paper or work about the platen. The body of the paper fingers may be in the form of narrow metal strips, and at their lower ends may each have a substantially C-shaped part 106, which is adapted to slidely hold each paper finger upon a guide bar. One of the paper fingers is held to a bar 107 and the other finger is held to a bar 108. The bar 107 is held to the carriage end piece 26, and the bar 108 to the carriage end piece 25, so that said bars may be extended or moved relatively and with the end pieces during the extension of the carriage, and such extension will also cause the fingers to move therewith, and by reason of the connection between the paper fingers and the bars said fingers may be adjusted to the desired distance for properly holding the work about the platen.

It will be understood that any desired form of line spacing mechanism may be employed to rotate the platen. As one means, a ratchet wheel 109 is held to one end of the platen and adapted to engage the teeth of the ratchet wheel is a pawl 110 mounted upon a lever 111. The movement of the pawl and the number of teeth engaged thereby is controlled by a stop, as 112, Fig. 3, to adapt the platen to be rotated a single, double, or more spaces. This mechanism, however, is substantially the same as that employed in the Corona typewriter, and is not claimed specifically herein, it being shown for the purpose of illustrating how such mechanism may be mounted in a carriage constructed and operating in the manner disclosed herein.

It will be evident that by the construction shown simple means is provided whereby the platen may be lengthened or shortened or the carriage lengthened or shortened;

that effective means is provided whereby the carriage may travel various normal and abnormal distances according to whether the carriage and the platen are lengthened or shortened, and without the necessity of interfering in any way with the feeding mechanism; that simple and efficient means is provided whereby the carriage may travel properly along its bed; that simple and efficient escapement mechanism is provided to adapt the carriage to have normal and abnormal travel; that the carriage is so constructed that it may be readily made and assembled and the parts thereof positively held against relative movement both in its lengthened and shortened condition; that simple and efficient means is provided whereby a paper apron may be adjusted lengthwise of the carriage; and that simple means is provided whereby the coöperating parts usually employed in connection with the platen and as a part of the carriage are so constructed that they may perform the usual function and properly coöperate with the platen to hold the work while being written upon.

In the prior application filed by myself and J. A. E. Criswell, Serial No. 70,611, filed January 6, 1916, there is illustrated and claimed a platen roll which is extensible (i. e., capable of being shortened or lengthened), but in that case the platen (i. e., writing or impact surface) is not capable of being varied as to length. My present structure differs from said structure in that I provide for shortening and lengthening the platen proper, that is, the impact or writing surface of the roll.

Having thus described my invention, I claim as new and desire to secure by Letters Patent:—

1. In a typewriting machine, the combination of a support, a carriage adapted to travel along said support, a platen mounted upon the carriage, means whereby the carriage may be lengthened or shortened, and means controlling the travel of the carriage along the support for distances corresponding to the different lengths of the carriage.

2. In a typewriting machine, the combination of a support, a carriage adapted to travel along said support, an extensible platen mounted upon the carriage, means whereby the carriage may be lengthened or shortened, and means controlling the travel of the carriage along the support for distances corresponding to the different lengths of the carriage.

3. In a typewriting machine, the combination of a support, an extensible carriage adapted to travel along said support, a rack, and two sets of escapement elements adapted to coöperate with the rack for letter spacing movement of the carriage either simultaneously or one at a time.

4. In a typewriting machine, the combination of a support, an extensible carriage adapted to travel along said support, a rack, and two sets of escapement elements mounted on one extensible part of the carriage adapted to coöperate with the rack for letter spacing movement of the carriage.
5. In a typewriting machine, the combination of a bed, a carriage adapted to travel along said bed and having relatively movable members whereby the carriage may be lengthened or shortened, and means controlling the travel of the carriage along the support for distances corresponding to the different lengths of the carriage.
6. In a typewriting machine, the combination of a support, a normally fixed rack, an extensible carriage movable on said support, and two sets of escapement elements mounted upon the carriage and adapted simultaneously to engage the rack of one at a time and thereby control the travel of the carriage along the support for distances corresponding to the different lengths of the carriage.
7. In a typewriting machine, the combination of a carriage bed, two track members held to said bed, an extensible carriage adapted to move along said track members and an extensible platen having its ends supported by said carriage.
8. In a typewriting machine, the combination of a carriage bed, track members, an extensible carriage adapted to move along said track members, and a sectional platen having its ends supported by said carriage.
9. In a typewriting machine, the combination of a carriage bed, two track members held to said bed, an extensible carriage adapted to move along said track members, and an extensible sectional platen having its ends supported by said carriage.
10. In a typewriting machine the combination of a support, an extensible carriage mounted upon said support, and an extensible platen rotatably held in said carriage.
11. In a typewriting machine, the combination of a support, an extensible carriage mounted upon said support, and an extensible platen having its ends rotatably supported in said carriage.
12. In a typewriting machine, the combination of a support, an extensible carriage mounted upon said support, and an extensible and sectional platen supported in said carriage.
13. In a typewriting machine, the combination of a carriage bed having a track way thereon, an extensible carriage having two substantially U-shaped members relatively movable with respect to each other and each provided with a carriage end bracket to adapt the carriage to be lengthened or shortened, means whereby the members of the carriage may be held against relative move-
ment, rolls carried by the carriage adapted to move along the track way, and a platen supported at its ends in said end brackets.
14. In a typewriting machine, the combination of a carriage bed, an extensible carriage having two members relatively movable lengthwise with respect to each other to adapt the carriage to be lengthened or shortened, means whereby the members of the carriage may be held against relative movement and an extensible platen supported at its ends in said carriage.
15. In a typewriting machine, the combination of a support, an extensible carriage having a plurality of lengthwise relatively movable members to adapt the carriage to be lengthened or shortened, means whereby the members of the carriage may be held against relative movement, and an extensible platen supported in the carriage.
16. In a typewriting machine, the combination of a support, a carriage having an inner substantially U-shaped member provided at one end with a carriage end bracket, a second member slidably held upon the first mentioned member, and provided with an end bracket, angular plates secured to the second member to adapt the two members of the carriage to be held together and still permit relative movement thereof, shafts mounted upon one member of the carriage, rolls held to said shafts, track members along which the rolls are adapted to travel, means for permitting the carriage members to be adjusted and to hold the same in an adjusted position, and a platen mounted in the carriage.
17. In a typewriting machine, the combination of a support, a carriage having an inner substantially U-shaped member provided at one end with a carriage end bracket, a second member slidably held upon the first mentioned member, and provided with an end bracket, angular plates secured to the second member to adapt the two members of the carriage to be held together and still permit relative movement thereof, means for permitting the carriage members to be adjusted and to hold the same in an adjusted position, and a platen mounted in the end brackets of the carriage.
18. In a typewriting machine, the combination of a support, a carriage having an inner substantially U-shaped member, a second member slidably held upon the first mentioned member, angular plates secured to the second member to adapt the two members of the carriage to be held together and still permit relative movement thereof, means for permitting the carriage members to be adjusted and to hold the same in an adjusted position and an extensible platen supported at its ends in the carriage.
19. In a typewriting machine, the combination of a support, an extensible carriage

- having relatively movable members, a dog carried by one member and adapted to engage the other to hold the carriage members against relative movement, means for disengaging the dog, and a platen mounted in the carriage.
20. In a typewriting machine, the combination of a support, an extensible carriage having relatively movable members, a dog carried by one member and adapted to engage the other to hold the carriage members against relative movement, means for disengaging the dog, and an extensible platen mounted in the carriage.
- 15 21. In a typewriting machine, the combination of a support, an extensible carriage having relatively movable members, means carried by one member and adapted to engage the other to hold the carriage members against relative movement, and an extensible platen mounted in the carriage.
- 20 22. In a typewriting machine, the combination of a support, an extensible carriage adapted to move along said support, and a platen comprising a plurality of detachable sections mounted upon said carriage.
- 25 23. In a typewriting machine, the combination of a support, an extensible carriage adapted to move along said support, and a roll platen journaled in the carriage comprising a plurality of detachable sections mounted upon said carriage.
- 30 24. In a typewriting machine, the combination of a support, an extensible carriage adapted to travel along said support, a platen having two end sections and a detachable intermediate section, and means for rotatably holding the platen in the carriage.
- 35 25. In a typewriting machine, the combination of a support, an extensible carriage adapted to travel along said support, and a platen having two end sections and a detachable intermediate section supported at its ends in the carriage.
- 40 26. In a typewriting machine, the combination of a support, an extensible carriage adapted to travel along said support and having end brackets, adjustable screws arranged in said end brackets, a platen comprising a plurality of sections, sleeves having threaded openings for engagement with the screws, line spacing means mounted upon one of the sleeves to rotate the platen, said platen having its sections provided with male and female socket members, and an intermediate section provided also with male and female socket members whereby said intermediate section may be readily attached to or detached from the other sections.
- 45 27. In a typewriting machine, the combination of a support, an extension carriage adapted to travel along said support, adjustable screws, a platen comprising a plurality of sections having socket members arranged in the end sections to engage said screws, said platen having its sections provided with male and female socket members, and an intermediate section provided also with male and female socket members whereby said intermediate section may be readily attached to or detached from the other sections.
- 50 28. In a typewriting machine, the combination of a support, an extensible carriage adapted to travel along said support, a platen comprising a plurality of sections provided with male and female socket members, and an intermediate section provided also with male and female socket members whereby said intermediate section may be readily attached to or detached from the other sections.
- 55 29. In a typewriting machine, the combination of a carriage, a platen mounted in said carriage, a paper apron, a guide, a slide connected to the paper apron and movable along said guide, a dog adapted to engage the guide and lock the apron in different positions lengthwise of the platen, and a lever for releasing the dog.
- 60 30. In a typewriting machine, the combination of a support, an extensible carriage adapted to travel along said support, a platen mounted to rotate in the carriage, and an extensible scale located in front of the platen comprising a plurality of relatively movable members.
- 65 31. In a typewriting machine, the combination of a support, a carriage adapted to travel along said support, a platen mounted to rotate in the carriage and an extensible scale located in front of the platen.
- 70 32. In a typewriting machine, the combination of a support, a carriage adapted to travel along said support and having relatively movable members to adapt the carriage to be lengthened or shortened, a bar movable with one member of the carriage, a second bar movable with the other member of the carriage, and paper fingers adjustable along said bars.
- 75 33. In a typewriting machine, the combination of a support, a carriage adapted to travel along said support and having means whereby the carriage may be lengthened or shortened, an extensible platen mounted in the carriage, escapement mechanism a part of which is mounted to travel with the carriage, and means for operating the escapement or releasing the same.
- 80 34. In a typewriting machine, the combination of a support, a carriage adapted to travel along said support and having means whereby the carriage may be lengthened or shortened, a platen mounted in the carriage, escapement mechanism a part of which is mounted to travel with the carriage and extensible means for operating the escapement.
- 85 35. In a typewriting machine, the combination of a support, a carriage adapted to

travel along said support, a dog carrier mounted to travel with the carriage, an extensible bar adapted to actuate the dog carrier, arms for supporting the extensible bar, and reciprocatory means independent of the carriage for operating the extensible bar.

36. In a typewriting machine, the combination of a support, a carriage adapted to travel along said support, a dog carrier mounted to travel with the carriage, an extensible bar adapted to actuate the dog carrier, and arms for supporting the extensible bar.

37. In a typewriting machine, the combination of a support, a carriage adapted to travel along said support, a dog carrier, an extensible bar adapted to actuate the dog carrier, arms for supporting the extensible bar, and reciprocatory means independent of the carriage for operating the extensible bar.

38. In a typewriting machine, the combination of a support, a carriage adapted to travel along said support, escapement mechanism, a bar adapted to actuate the escapement mechanism to control the letter feed movement of the carriage, means for actuating the bar independent of the carriage, and manually operated means mounted on the carriage for operating said bar to permit the carriage to be released.

39. In a typewriting machine, the combination of a support, a carriage adapted to travel along said support, escapement mechanism, a bar adapted to actuate the escapement mechanism to control the letter feed movement of the carriage and manually operated means mounted on the carriage for operating said bar to permit the carriage to be released.

40. In a typewriting machine, the combination of a support, a carriage adapted to travel along said support, having means whereby the carriage may be extended or collapsed, a rack mounted upon and movable with the carriage, and two dog carriers mounted upon the support and coöperating with the rack independently or together.

41. In a typewriting machine, the combination of a support, a carriage adapted to travel along said support having means whereby the carriage may be extended or collapsed, a rack mounted upon and mov-

able with the carriage, and independent escapement means coöperating with the rack 55 independently or together.

42. In a typewriting machine, the combination of a support, a carriage adapted to travel along said support, a rack mounted upon and movable with the carriage, and 60 escapement means mounted upon the support and coöperating with the rack independently or together.

43. In a typewriting machine, the combination of a support, an extensible carriage 65 adapted to travel along said support, a non-extensible rack and means located at different distances along the support and coöperating with the rack and acting on the rack together or independently to permit the carriage to have a relatively long travel along 70 said support.

44. In a typewriting machine, the combination of a support, an extensible carriage adapted to travel along said support, a non-extensible rack, and independent escapement means located at different distances along the support and coöperating with the rack and acting on the rack together or independently to permit the carriage to have a relatively long travel along 75 said support.

45. A typewriting machine, having a platen support, a platen formed of relatively movable sections each having a surface adapted to receive the impact of the type, and means whereby the impact surfaces of any desired number of said platen sections may be supported in juxtaposition and in longitudinal alinement with each other on said platen support to provide a 80 continuous impact-receiving surface of the desired length.

46. In a typewriting machine, the combination of a longitudinally extensible and contractible platen carriage, a cylindrical 95 platen roll having end sections journaled on said carriage and a detachable intermediate section, and means whereby the inner ends of said end sections may be operatively connected to cause said end sections to rotate in unison when said intermediate section is removed and the carriage is shortened to bring said end sections in juxtaposition.

This specification signed this 20th day of April, A. D. 1916.

BENJAMIN W. TUCKER.
